UNITED STATES PATENT OFFICE.

JOHN B. HARRISON, OF CINCINNATI, OHIO.

MEANS FOR RAISING LIQUIDS.

SPECIFICATION forming part of Letters Patent No. 364,512, dated June 7, 1887.

Application filed February 23, 1887. Serial No 228,565. (No model.)

To all whom it may concern:

Be it known that I, JOHN BERNARD HARRISON, of Cincinnati, in the county of Hamilton and State of Ohio, have invented a new and useful Improvement in Means for Raising Liquids and Supplying Same through Sealed Pipes to Factories, which improvement is fully set forth in the following specification and accompanying drawing, in which the figure is a perspective view of my device for raising water or oil and supplying same through sealed pipes to factories.

My invention relates to an improvement in devices for raising water discharged from Artesian wells above the height of the normal flow of water, or for raising oil and discharging it into tanks, and for removing the offensive gases from the same and discharging them through the stack, and preventing the said gases from the mineral water entering the tanks and thence passing through the connecting-pipe into the building; and it consists of a vertical pipe connected with a well-tubing, and extending forty feet or more above the normal height of the water or oil pipes, the said pipe having another pipe connecting with a series of tanks, so that the water or oil may flow into the said tanks when at a normal height in the well-pipe, while the upper end of said well-pipe leads into an inclined pipe that is connected with the upper ends of the reservoir or tanks, and also with a smoke-stack, so that the draft through the smoke-stack will carry off the offensive odors arising from the mineral water or oil within the tanks and stand-pipe, and at the same time rarefy the atmosphere within the pipes, and thus raise the water or oil in the vertical pipe and cause it to flow into the tanks, all of which will now be fully set forth in detail.

In the accompanying drawing, A represents an ordinary smoke-stack of a furnace, and B air-tight water-tanks. I conduct the tubing C of Artesian or oil wells to a point near to, or preferably between, the tanks and the furnace, so that the vertical pipe C passes up between them; or if the oil or Artesian wells have been located and the smoke-stacks are afterward placed in position, I prefer that this smoke-stack, flue, or chimney should be placed as closely as possible to the well-tubing.

In the drawing I represent a well-tubing, C, which originally terminated at the point C', and the water or oil from the tubing C would not rise above that height; or, in other words, the normal pressure of the liquid from the well would not cause it to flow above the point C'. To this tubing C, I have added a vertical extension, E, for a distance of forty feet or more, where it connects with an inclined pipe, F, opening at its upper end into the smoke-stack A, its opposite end connecting by means of pipes G and H with the tanks B.

Near the upper part of each tank B, I place a horizontal discharge or overflow pipe, I, the down part of which is provided with a goose-neck or trap, J, through which the water may be conveyed into the building for use. The object of this trap is to cut off air which would otherwise find its way into the tanks through the pipe I. This overflow-pipe I is placed preferably on a line with the normal level of the water in the well-tube. (Represented by C' in pipe C.)

The tube C is provided with a horizontal pipe, K, connecting with a sewer or other waste-outlet. This pipe K has a safety-valve, L, while the upper part of the pipe E is provided with a valve, M, so disposed that when the water rises to a dangerous height within the pipe E the valve M, which is connected with the safety-valve L by means of a rod, N, opens the safety-valve and permits the surplus water to be discharged through the pipe K into the sewer. The construction of this valve or automatic cut-off is immaterial to the present invention, but it is obvious that various mechanical means may be resorted to to accomplish this purpose. The inclined pipe F, which connects with not only the vertical pipe E from the well-tubing but also with the pipes G H on top of the inclosed tanks B, being connected with the draft-flue A, it is evident that any rarefaction of the atmosphere within the pipe F will act equally upon the liquid in the tanks B and pipe E, thereby causing the liquid to rise in proportion to the draft of the flue A. At the same time the supply-pipe D, from the well-tubing C, being connected with the tanks below the top outlet-pipes, G H, the liquid will readily flow into the tanks as fast as the displacement of air

takes place. In practice I prefer to supply the tanks by means of pipes on the lower end of the tanks, as shown in Fig. 1; but it is obvious the pipe D may enter the tanks at any point along the side.

The operation of my device is as follows: The pipe D, connecting with the well-tubing C, being at or below the normal pressure point, so as to discharge the liquid from the said tube into the tanks B, will fill the said tanks to a height corresponding with the normal pressure of the liquid in the pipe C. As the points E and F are connected with the smoke-stack A, and the draft from the said stack causes a rarefaction within the pipes E and F, the normal atmospheric pressure is thus removed from the water flowing through the connecting-pipe D and also from the water in the tanks, and thus permits it to be elevated in the pipe E. If the air within the tubes E and F is sufficiently rarefied by the draft through the chimney A, so as to form a perfect vacuum, the water will rise within the tube E thirty-three feet above the normal point C', or so many feet above the height of the water flowing through the tube C at a normal pressure. In proportion as the water rises in the pipe E the water rises in the tanks B. As will readily be noticed, the connecting-pipe D from the tube C may enter the tanks B at any suitable height, and also the same may be said of the discharge-pipe I.

As it is a well-known fact that the gases rising from the water of Artesian wells are destructive to the tubes and pipes and metallic work of buildings, and also have very offensive odors, my device is designed, in addition to its elevating properties, to carry off these offensive and destructive odors from the pipes, as well as from the tanks B, and discharge them into the chimney A. It is also obvious that by this arrangement I am enabled to locate my tanks one or two floors above the normal discharge of the liquid from the well-tubing, and in practice this will be done in every case. Where the chimney cannot be provided of sufficient height to create the requisite draft, I design placing a steam-jet in the flue or chimney, as shown at O. This pipe is directed upwardly and will cause a strong draft in the flue of sufficient force to raise the liquid in the pipe to the requisite height, and thus accomplish all that I aim to do with the draft from the furnace operating through the flue A.

55 What I claim is—

1. In a water-elevating device for wells, the main well-tubing connected directly with a smoke-stack or draft-flue, whereby the air within the well-tube above the water will be rarefied by the draft of the flue and permit 60 the water to rise in said well-tube above its normal level, substantially as herein set forth.

2. In a means for raising water and supplying same through sealed pipes to factories, a main vertical pipe from the well, connected 65 with the body of the tanks by a branch pipe at its upper end, an inclined pipe being also connected with the stack, so that the air within this pipe may be rarefied, and thus remove the pressure of the air from the head of the well-tubing and permit the water to rise in the pipes and overflow into the tanks at a higher 70 level than otherwise, substantially as herein set forth.

3. In a means for raising water and supplying same through sealed pipes to factories, the pipe D, connecting directly with both the well-tubing C and tanks B, and a second system of pipes, E, F, G, and H, connecting with the stack, so as to be rarefied by the draft, and thus carry 75 off the offensive gases and odors, and also elevate the water within the tubes to a greater 80 level, substantially as herein set forth.

4. In a means for raising water and supplying same through sealed pipes to factories, a 85 tube, C, provided with a pipe, D, connecting the tanks B and pipe E, at the upper part, with the inclined pipe F, also connecting with the tanks B, said tubes having a waste-pipe, K, provided with a safety-valve, L, operating in 90 connection with a valve, M, at the upper part of the pipe E, substantially as herein set forth.

5. The combination of the tanks B, having a connecting-pipe, D, joined to a tube, C, conveying-pipe I, and trap J, with vertical pipes 95 G and H, inclined pipe F, and pipe E, substantially as herein set forth.

6. The combination of the tanks B, having conveying-pipes I, pipes G and H, and inclined pipe F, with the pipe E, chimney A, 100 connecting-pipe D, and tube L, substantially as herein set forth.

In testimony that I claim the foregoing I have hereunto set my hand, this 15th day of December, 1886, in the presence of witnesses.

JOHN B. HARRISON.
